UNITED STATES PATENT OFFICE.

JAMES H. GRAY, OF CLEVELAND, OHIO.

SADIRON.

Application filed March 9, 1920, Serial No. 364,426. Renewed January 16, 1923.

To all whom it may concern:

Be it known that I, JAMES H. GRAY, a citizen of the United States, residing at Cleveland, in the county of Cuyahoga and 5 State of Ohio, have invented certain new and useful Improvements in Sadirons, of which the following is a specification.

This invention relates to improvements in sad-irons, and pertains especially to devices of that class which are adapted to the employment of gasoline or petroleum as a heating medium, a supply of which is stored in a suitable tank connected with the sad-iron.

15 The object of the invention is to produce a sad-iron of simple, durable and economical construction, employing liquid fuel such as petroleum or gasoline as a heating medium, and providing a new and improved arrangement of gas generating structure.

The invention further provided a compact, non-cumbersome construction that makes the sad-iron safe and convenient to manipulate.

25 With the above and other objects in view which will appear as the description proceeds, the invention resides in the combination and arrangement of parts and in the details of construction hereinafter described 30 and pointed out definitely in the appended claims, it being understood that changes in the precise embodiment herein disclosed can be made without departing from the spirit of the invention, providing such changes 35 are within the scope of the claims.

In the accompanying drawings, which are made part of the specification, Figure 1 is a plan view of an embodiment of the improved sad-iron.

40 Fig. 2 is a vertical, longitudinal section on line 2—2 of Fig. 1, showing certain elements, which will be identified, in elevation. Fig. 3 is a plan view with the body cap and fuel tank removed. Fig. 4 is a rear view. Fig. 45 5 is a vertical section on line 5—5 of Fig. 1, and Fig. 6 illustrates a modified arrangement of certain elements.

Throughout the description and in the drawings, similar characters of reference are 50 employed to designate corresponding parts.

The body of the sad-iron is made of two parts, a cast-iron base member 1, and a cap 2 which is preferably a metal stamping formed substantially as shown, so as to provide a chamber 3 when the elements are assembled. I prefer to provide the outer sur-

face of the cap 2 with a coating of heat-proof enamel. This not only gives the article an attractive appearance, but it is beneficial from a sanitary and economic 60 standpoint. It makes the sad-iron easy to keep clean, and prevents oxidization or the formation of rust. I am aware that sad-irons have heretofore been provided with an exterior nickel finish. Such a finish is 65 not impervious to the excessive heat to which it is subjected, and therefore is not the equivalent of the heat-proof enamel as a protective agent.

The base member 1 is provided with a 70 pillar 1^a preferably cast integral therewith. Said pillar serves as a support for all the elements that are embodied in the structure. A handle 4 is connected with the cap 2, and a heat shield 5 is provided, said shield and 75 cap being attached to the pillar 1^a by screws 6 and 7, spacing members 8 being provided to allow air space 9 between the shield 5 and the top of the cap 2.

A fuel tank 10 is provided with a feed 80 pipe 11 which connects with a combined feed and generator member of novel construction and arrangement. This generator comprises a pipe having a branch 12 connected with the feed pipe 11 and extending 85 longitudinally in the chamber 3, through an opening 1^b in the pillar 1^a, and having a loop 12^a which provides for a return branch 12^b which passes through the opening 1^b and is connected with the needle-valve 90 fitting 13. The screw 6 bearing on the generator member retains said member in place.

The burner 14 provided with jet apertures 14^a, is located below the generator and is supported by the pillar 1^a, as shown in Figs. 95 2, 3 and 5, the needle-valve 13^a connecting with the flared open end 14^a of said burner. Air is admitted for the proper combustion mixture through the opening 2^a. Ventilation is provided by a series of apertures 2^b in 100 the cap 2.

The base member 1 is formed with a depression 15 which provides a receptacle for a priming medium, preferably alcohol. In practice the depression 15 is filled with alcohol or other volatile fluid, through the opening 2^a. The fluid thus disposed, when ignited provides the initial gas-generating means, the heat from the primer acting on the pipe members 12, 12^a and 12^b volatilizing 105 or gasifying the liquid flowing through said pipe. The priming heat also acts on the 110

burner member 14, so that the needle-valve 13^a may be opened at the start and the jets become ignited at the apertures 14^b. The peculiar formation and arrangement of the 5 supply pipe, having the branches 12 and 12^b and the loop 12^a, extending forward and back in the chamber 3, provides an extensive area which is acted upon by the heat from the burner, making a highly efficient genera- 10 tor which particularly adapts the device for the use of petroleum as a fuel medium.

In Fig. 6 the fuel tank 10^a is shown embodied in the handle member 4^a, the fuel feed pipe 11^a connecting with the generator. Otherwise the construction of the 15 sad-iron is the same as hereinbefore described. As the amount of liquid fuel required for several hours of continuous operation of the device is not great, a tank of 20 sufficient capacity may be conveniently located in the handle, or connected therewith in various practical ways.

What I claim and desire to secure by Letters Patent is:

25 1. In a sad-iron using liquid hydrocarbon as a fuel, the combination of a base, a pillar integral with said base, a cap attached to said pillar and coacting with the base to form a heat chamber, said cap being pro- 30 vided with ventilating openings, a handle connected with the cap, a heat shield supported by the pillar, under the handle pro-

viding an air space between said shield and the cap, a fuel tank, a looped generating feed pipe extending from said tank longitudinally in the chamber and supported by the pillar, a needle-valve connected with said pipe, a burner member coacting with said needle-valve, supported by the pillar and extending longitudinally in the chamber beneath the generator pipe and over the fluid receptacle in the base. 35 40

2. In a sad-iron using liquid hydrocarbon as fuel, the combination of a base, a pillar integral with said base, a cap attached to 45 said pillar and coacting with the base to form a heat chamber, said cap being provided with ventilating openings, a handle connected with the cap, a heat shield supported by the pillar under the handle, pro- 50 viding an air space between said shield and the cap, a fuel tank connected with the handle, a looped generating feed pipe extending from the tank longitudinally in the chamber and supported by the pillar, a needle-valve connected with said pipe, a burner member coacting with said needle- 55 valve, supported by the pillar and extending longitudinally in the chamber beneath the generating pipe and over the fluid receptacle 60 in the base.

In testimony whereof I affix my signature.

JAMES H. GRAY.
